HARRY T. NAUMAN, OF LOS ANGELES, CALIFORNIA

GAME APPARATUS

Application filed October 7, 1930. Serial No. 486,880.

My invention relates to game apparatus, and particularly to game apparatus requiring skill in the playing thereof.

The objects of this invention are: first, to provide a game apparatus having a multiplicity of different goals or holes into which may be driven or projected the game members used, depending upon the skill of the player, the high score depending upon the accuracy or proficiency of the player in directing the game members into the holes or goals chosen; second, to provide a game apparatus having a multiplicity of holes, or other goals, which are provided with designations corresponding to the card designations of a poker deck of cards, so that a competitive poker game may be played with the apparatus, or whereby each player may seek to make a high score from each series of plays for a prize to be won; third, to provide an apparatus of this class in which there is provided a visible registering member for each goal which is visibly displayed when a particular goal is made; fourth, to provide such an apparatus in which a deflector is raised in front of each goal as such goal is scored so as to reduce to a minimum the possibility of scoring the same goal twice; fifth, to provide an apparatus of this class which is played with balls and a putter and in which there is a direct line passage for the ball from the starting tee or space to each of the holes so that a skilful player may drive the balls into the desired holes or other goals having a predetermined scoring value; sixth, to provide a game apparatus in which the holes or goals are arranged at the upper portion of an inclined platform so that the balls may return to the player when the same are not struck with sufficient force or accuracy; seventh, to provide a game apparatus of this class in which the balls, when driven beyond the holes and are driven up a steeper inclined portion beyond the holes, whereby control of the ball is lost and the same either enters an unselected hole or returns to the player; eighth, to provide novel means for registering the score of a particular goal and for shifting the ball deflecting member of the particular goal into place; ninth, to pro-

vide novel and simple means for holding all of the balls in a certain operative relation with the registering and deflecting means of each goal so that the total score of one player may be retained and seen by the other players or attendant; tenth, to provide a simple ball return alley which is adapted to return the balls to the player end of the game apparatus at substantially the starting level of the platform; eleventh, to provide novel gate means in connection with the ball return alley whereby a second set of balls is retained and released when desired, and such gate means is operatively connected to a gate means in direct association with the holes or goals, which latter gate means is released for releasing the balls in the goals for placing the same within the alley to be released when the gate means is again actuated, thus providing a game apparatus in which a minimum number of balls are used and in which a set of balls is always at hand for the player when desired; twelfth, to provide novel coin controlled means for actuating the gate means to perform the above mentioned functions; thirteenth, to provide as a whole a novelly constructed game apparatus of this class; and fourteenth, to provide such a game apparatus which is very simple and economical of construction proportionate to its functions, durable, one which is easy to operate, one which a player may easily learn to play, and a game apparatus which will not readily deteriorate and get out of order.

With these and other objects in view as will appear hereinafter, I have devised a game apparatus having certain novel features of construction, combination and arrangement of parts and portions as will be hereinafter described in detail, and particularly set forth in the appended claims, reference being had to the accompanying drawings and to the characters of reference thereon which form a part of my application in which:

Figure 1 is a plan view of my game apparatus in one form; Fig. 2 is a fragmentary sectional elevational view thereof, taken at 2-2 of Fig. 1; Fig. 3 is an enlarged fragmentary sectional view thereof taken through 3-3 of Fig. 1 showing the lever and link connection

for operating the gates; Fig. 4 is an enlarged fragmentary sectional plan view thereof taken through 4-4 of Fig. 2 showing the ball control gate and the operating mechanism therefor, and showing by dotted lines one of the gates in a closed position and the other gate in its open position; Fig. 5 is an enlarged sectional elevational view thereof taken through 5-5 of Fig. 1 showing the 10 upper portion of the inclined platform and one of the holes and the trip member and gate in connection therewith and showing by dotted lines certain moved positions of the ball deflector, trip hammer and gate when the ball is dropped into the hole and when the same is released; Fig. 6 is a fragmentary plan view on an enlarged scale of one of the holes and the deflecting member and trip member in connection therewith; Fig. 7 is a fragmentary sectional elevational view thereof taken at 7-7 of Fig. 5 showing the score indicia in connection with some of the holes and showing the deflecting and registering members of one of the holes in a raised position; Fig. 8 is a fragmentary sectional elevational view taken through 8-8 of Fig. 4; Fig. 9 is an enlarged sectional elevational view taken through 9-9 of Fig. 1 showing the coin actuated means for operating the several gates; Fig. 10 is an enlarged fragmentary sectional elevational view of the coin actuated means taken through 10-10 of Fig. 9; Fig. 11 is a sectional view thereof taken through 11-11 of Fig. 9 showing the coin slot; and Fig. 12 is a fragmentary sectional elevational view thereof taken through 12-12 of Fig. 11.

Like characters of reference refer to similar parts and portions throughout the views of the drawings.

The field of play of my game apparatus, illustrated in the drawings, consists of a platform 1 which is relatively long and diverges from its starting end toward the end 1b in which the goals are provided. This platform is also inclined upwardly from its starting end toward the opposite end in a gradual incline, the incline being such that the balls not entering the goals will be returned to the starting end. If desired, the starting end or space may be horizontal, or may be provided with a roughened portion or ridges for placing the same in order to strike the ball with a putter or other club or device. At the wide end 1b of the platform is provided a transverse row of goals which are in the form of holes 1c. These holes are so located that they are all accessible by direct shots from the starting space or tee 1a. The platform beyond the holes 1c is inclined at a greater angle than the main field of play of the platform. This greater inclined portion, designated 1d, is adapted to retard the movement of the balls if they should be struck beyond the holes. This inclined portion 1d will also give considerable momentum to the ball as it is re-

turned and will tend to cause the balls to return to the starting space.

The holes 1c are of sufficient size to receive wholly therein the balls or other game members used. The game members are preferably the same as those used in playing golf. The holes are all labeled with different designations or indicia and of predetermined relative values. Such indicia are painted or otherwise inscribed on the greater inclined portion 1d of the platform and directly behind the respective holes, as indicated by 2 in Figs. 1 and 7. These indicia or designations are the same as the designations on the cards of an ordinary poker deck, such as the queen of hearts, king of diamonds, and seven of clubs, shown in Fig. 7. There may be provided as many holes as there are cards in the poker deck, or any number of holes less than the total number of cards in such a deck, depending upon the available space for the apparatus or the amount of money desired to be spent upon the apparatus.

The rules for scoring in playing the game may be the same as those used in playing the game of poker, either when playing for prizes or when playing a competitive game. Because of its similitude to the game of poker, in which five cards are used to each hand of the players, the game is preferably played with five balls and each ball driven into one of the pockets or holes corresponds to one of the cards in the hands of the poker player. All of the five balls of each player are driven into the holes before the turn of the next player, so that the complete score of a player may be registered in turn. In connection with each hole, there is provided a registering means for visibly indicating to all of the players and the attendants, the total score of a player.

The aforementioned registering means is actuated by a trip member 3, one of which is provided in connection with each hole. This trip member, which is in the form of a trap door, consists of a plate which is pivotally mounted intermediate its forward and rear ends on and at the lower end and rear side of the hole member 4. This hole member is preferably in the form of a cylindrical member provided at its upper end with a flange which supports the member at its upper end in the hole 1c of the platform. The lower portion of the rear side of the hole member 4 is provided with an opening 4a through which the ball is adapted to roll toward the rear end of the trip member, as will be described hereafter. Within the hole member is positioned a registering member 5, shown best in Figs. 5, 6 and 7. This registering member is arcuate and conforms with the interior of the pocket member and is positioned at the forward side of the hole member. This registering member is reciprocally mounted in a vertical direction at its lateral

- edges between vertical guides 6 secured to the inner side of the hole member so that the registering member may be extended above the surface of the platform. The lower end 5 of the registering member is pivotally connected to the forward end of the trip member, this trip member being provided at its forward end with a downwardly and forwardly extending slotted lug 3a through which a pin 10 7, carried by the lower end of the registering member, extends, as shown best in Figs. 5 and 7. The trip member 3 is normally held in an inclined position by a pin or other means 8 so that when a ball enters the hole the ball 15 normally rolls backwardly, tilting the trip member to the dotted line position, shown in Fig. 5, and raising the registering member above the playing surface of the platform. When the ball is released from the trip member, as will be described hereafter, the weight 20 of the registering member normally returns the registering member and the trip member to the positions shown by solid lines in Fig. 5. On the front side of each registering member 25 is painted, stamped, or otherwise inscribed the score indicia for the particular hole, which indicia corresponds to the indicia 2 aforementioned for the particular hole.
- It will be here also noted that this registering means is positioned at the forward side of the hole and serves as a deflector or means for preventing another ball from entering the same hole from the front side. The registering member is also curved so that the 30 same will not be readily distorted and so that a ball struck thereagainst may be deflected into another hole.
- When the balls are released from the trip members or trap doors 3, the same are permitted to fall on to an inclined floor 11 immediately below the holes. This inclined floor extends completely across the underside 35 of the platform and is adapted to receive thereon the balls from all of the holes. The forward side of the inclined floor is bounded by a diagonal wall 11a, shown in Fig. 1, which permits the balls to roll to one side of the platform. At the lateral side or edge of the platform, namely, at the right hand 40 side, is provided a ball return alley 12 which is connected at its rear end to the lower portion of the inclined floor 11 and is adapted to receive the balls from said inclined floor when the balls are released from the trip means. The forward end of the alley 12 terminates 45 in an opening 12a from which the balls may be removed by the players. The ball delivery end of the alley 12 may terminate substantially on the level with the starting end 50 of the platform, depending upon whether the alley is positioned directly to one side or below the playing surface of the alley, and depending upon whether the gates, positioned in the alley, are operated from below or from 55 the side, as will be described hereafter.

At the rear portion of the inclined floor 11, below the platform 1, is mounted a long gate 16 which is pivotally mounted at its lower edge and extends with its upper portion beyond the rear ends of the trip members 3. This gate extends past the rear end of all of the trip members or trap doors, and is adapted to hold the balls on the latter, as shown by dotted lines in Fig. 5, until the gate 16 is tilted backwardly. The gate 16 is normally held in its ball holding position by a spring or springs 17. The gate 16 is prevented from closing quickly by a dashpot construction which consists of a cylinder 18 pivotally mounted at one end, a piston 19 reciprocally mounted therein and provided with a longitudinal bore 19a therethrough, and a piston rod 20 secured to the piston, extending through the head of the cylinder opposite its pivotal mounting, and pivotally connected at its outer end to the gate 16. The gate 16 may be tilted backwardly to the dotted line position by an operating lever at the player end of the platform. The gate 16 is indirectly connected to such lever by a cable 21 which is secured at one end to the upper portion of the gate, extends around a sheave 22, and is connected at its opposite end to one arm of a bellcrank lever 23. In the alley 12 are mounted two gates 24 and 25, the former being normally positioned in the path of the alley and adjacent the ball delivery end of the alley, and the latter being positioned intermediate the gates 16 and 24 and normally positioned outside of the path of the alley. The gate 24 opens or is shifted out of the path of the alley simultaneously with the backward tilting of the gate 16, while the gate 25 during such movement is forced across the path of the alley. The opposite movement of the gates are in the same order.

Both of the gates 24 and 25 are reciprocally mounted in a horizontal direction, movement being imparted thereto by a bellcrank 26 and the bellcrank 23, respectively. These bellcranks are pivotally mounted at the intersection of their arms on brackets 27 positioned outside of the alley and underneath the platform. These bellcranks are positioned in reverse order and are connected together with a link 28. This link 28 is pivotally connected to the arm of the bellcrank 23 to which the cable 21 is connected, the other arm of the bellcrank being connected to the gate 25. The opposite end of the link 28 is connected to the arm opposite to the one connected to the gate 24. The arm connected to the link 28 is also pivotally connected, by a link 29, to an arm 30 mounted on a rockshaft 31 which is rotatably mounted, in this instance, below the starting end of the platform and is controlled by the actuating lever aforementioned.

The actuating or control lever 36 is mount-

ed on a shaft 37 which extends into a vertical casing 38 enclosing the coin actuated mechanism and positioned at one side of the player end of the platform. Within the casing 38 and on the shaft 37 is mounted a coin receiving arm 39. This arm is provided at one side of its upper end with a narrow slot 39a which, when the arm 39 is in its normal position of rest, is aligned with a horizontal coin slot 40a in the coin receiving member 40 mounted at the upper end of the casing 38 and extending to the side thereof opposite the lever 36. At the upper portion of the coin receiving member 40 is provided a circular opening 40b into which a coin of the designated denomination is inserted. The coin is permitted to drop through a short substantially vertical slot 40c into the outer end of the coin slot 40a, as shown best in Fig. 12. The coin at the outer end of the coin slot 40a is forced inwardly by a manually actuated plunger 41 which forces the coin from the position A to the position B, the plunger 41 being returned to its outer position by a spring 42.

At the front side of the coin receiving member is positioned a transparent plate 43 through which the coins may be seen for determining whether any slugs have been inserted into the machine. There are normally three coins in the coin receiving member which occupy the positions B, C and D. When a fourth coin is inserted, it assumes the position A. When the plunger 41 is forced inwardly, the coin from the position D is forced into the coin slot 39a of the arm 39, placing the mechanism in an operating position. Within the coin receiving member and at the upper portion of the coin slot therein, are mounted two springs 43 and 44 which hold the coins in the positions B, C and D, until they are displaced by forcing inwardly the plunger 41. The spring 44 holds the coin in the position D until the same is displaced, as above described. The outer end of the arm 39 is also provided with a transverse slot 39b which intersects the slot 39a, but which is slightly narrower than the diameter of the coin, leaving a flange or retaining portion 39c, as shown in Figs. 9, 11 and 12, for preventing the coin from being displaced in the direction of the rotating arm. Within the casing, and slightly below and backwardly from the axis of the shaft 37, is rotatably mounted a shaft 45 on which is mounted an arm 46 which is in the form of a bellcrank lever. The one arm, designated 46a, extends upwardly in substantially the plane of the coin receiving arm 39 and is offset toward the side of the open end of the slot 39a and then extends with an offset arm 46b toward the free end of the arm 39. At the end of the offset arm 46b is rotatably mounted a roller 47 which is slightly less in diameter than the width of the slot 39b and permits the arm 39 to be rocked backwardly with the roller 47

passing through the slot 39b when no coin is in position in the slot 39a. However, if a coin has been forced into the slot 39a and the lever 36 is drawn backwardly, the coin in the slot engages the roller and causes the lever 46 to be rotated in the direction of the arm 39. After only a slight rotation of the lever 46, the roller is raised free from the coin and rides upon an inclined surface 39d at the front side and upper end of the arm 39. When the arm 39 is drawn backwardly, it also clears the end of the coin receiving member 40 and permits the coin in the slot 39a to leave such coin slot. To facilitate the discharge of the coin from the coin slot 39a, the lower edge of the slot is inclined downwardly, as indicated by 39e in Figs. 9 and 12. When there is no further resistance to the discharge of the coin from the arm 39, the coin drops into a coin box 48 which is positioned immediately to one side of the lever 46 and the arm 39, at the coin slot side of the latter. The coin box 48 may be mounted on a bracket within the casing 38 so that the coin box may be withdrawn from the back side of the casing, as shown in Fig. 10.

The other arm 46c of the bellcrank lever 46 is pivotally connected at its free end by a link 49 to the free end of an arm 50 which is mounted on the shaft 31 to which the arm 30 is secured. Thus, when the operating lever 36 is drawn backwardly with a coin in the coin slot of the arm 39, the arm 46a of the bellcrank lever 46 is also drawn backwardly forcing the arms 36b and 50 upwardly and the arm 50 and link 29 backwardly, which opens the gate 24 and tilts the gate 16 backwardly and forces the gate 25 across the path of the ball return alley. Such operation releases the balls from the trip members or trap doors 3 and permits the same to roll down the inclined floor 11 into the alley against the gate 25. Such operation also permits a second set of balls previously held by the gate 24 to be released and to roll into the pocket or ball delivery end of the alley. When the handle or lever 36 is released, the gate 16 is returned to its forward position and the gate 24 to its closed position across the path of the alley, while the gate 25 is withdrawn. Thus, the set of balls stopped by the gate 25 are permitted to roll down the alley against the gate 24 and are then held in readiness until the lever 36 is again drawn backwardly with another coin.

It will be here noted that the dashpot connected to the gate 16 retards the closing of this gate and also the movement of the gate 25 and 24. Such retarded movement permits all of the balls to escape from behind the gate 24 and also permits all of the balls in one pocket or hole to escape therefrom before the gate 16 reaches its forward position. If a second ball is dropped into a pocket, the same is held in the dotted line position, design-

nated E in Fig. 5. When the gate 16 is drawn backwardly, the original ball in the position F is permitted to drop, releasing the trip member allowing the same to fall to its 5 solid line position, shown in Fig. 5, and allowing the ball to roll toward the rear end of the trip member and again to tilt such trip member and to drop therefrom.

Though I have shown and described a particular construction, combination and arrangement of parts and portions of my game apparatus, I do not wish to be limited to this particular construction, combination and arrangement, but desire to include in the scope 15 of my invention the construction, combination and arrangement substantially as set forth in the appended claims.

Having thus described my invention, what I claim as new and desire to secure by Letters 20 Patent is:

1. In a game apparatus, a platform having a plurality of spaced holes at one end thereof, a registering member in association with each of the holes, a trip member in association 25 with each of the holes and operatively connected to the registering member of the respective hole for shifting said registering member into view when a ball enters the hole, and a gate member in association with all of 30 the trip members for retaining the balls thereon and the respective registering member in view, said gate being shiftable for releasing all of the balls for permitting the trip members and registering members to assume 35 their normal inoperative positions.

2. In a game apparatus, a platform having a plurality of spaced holes at one end thereof, a registering member in association with each of the holes, a trip member in association 40 with each of the holes and operatively connected to the registering member of the respective hole for shifting said registering member into view when a ball enters the hole, a gate member in association with all of 45 the trip members for retaining the balls thereon and the respective registering member in view, said gate being shiftable for releasing all of the balls for permitting the trip members and registering members to assume 50 their normal inoperative positions, a ball return alley for receiving the balls when released by the gate, other gate means in association with the return alley adapted to close the same when the balls are released 55 by the first gate, and means for simultaneously operating said gate and gate means.

3. In a game apparatus a platform having a plurality of spaced holes at one end thereof a registering member in association with 60 each of the holes, a trip member in association with each of the holes and operatively connected to the registering member of the respective hole for shifting said registering member into view when a ball enters the 65 hole, a gate member in association with all

of the trip members for retaining the balls thereon and the respective registering member in view, said gate being shiftable for releasing all of the balls for permitting the trip members and registering members to assume 70 their normal inoperative positions, and coin controlled means for operating the gate and releasing the balls.

4. In a game apparatus, a platform having a plurality of spaced holes at one end thereof, a registering member in association with each of the holes, a trip member in association with each of the holes and operatively connected to the registering member of the respective hole for shifting said registering member into view when a ball enters the hole, a gate member in association with all of the trip members for retaining the balls thereon and the respective registering member in 75 view, said gate being shiftable for releasing all of the balls for permitting the trip members and registering members to assume their normal inoperative positions, a return alley extending from the space adjacent the gate to the starting end of the platform, the balls being adapted to be removed from the latter end of the alley, a second gate in association with the alley at the latter end thereof, and a third gate in association with the alley intermediate the first and second gates, and means for simultaneously actuating all of said gates, the first and second gates being opened and closed simultaneously, and the third gate being closed and opened alternately with respect to the first and second gates. 80

5. In a game apparatus, a platform having a plurality of spaced holes at one end thereof, a registering member in association with each of the holes, a trip member in association with each of the holes and operatively connected to the registering member of the respective hole for shifting said registering member into view when a ball enters the hole, a gate member in association with all of the trip members for retaining the balls thereon and the respective registering member in view, said gate being shiftable for releasing all of the balls for permitting the trip members and registering members to assume their normal inoperative positions, a return alley extending from the space adjacent the gate to the starting end of the platform, the balls being adapted to be removed from the latter end of the alley, a second gate in association with the alley at the latter end thereof, and a third gate in association with the alley intermediate the first and second gates, and a coin controlled means for simultaneously actuating all of said gates, the first and second gates being opened and closed simultaneously, and the third gate being closed and opened alternately with respect to the first and second gates. 100

6. In a game apparatus, a platform having a plurality of spaced holes at one end thereof, 105

- a registering member in association with each of the holes, a trip member in association with each of the holes and operatively connected to the registering member of the respective 5 hole for shifting said registering member into view when a ball enters the hole, a gate member in association with all of the trip members for retaining the balls thereon and the respective registering member in view, 10 said gate being shiftable for releasing all of the balls for permitting the trip members and registering members to assume their normal inoperative positions, means for opening said gate for releasing said balls from the trip 15 means, and means for closing and for retarding the closing of said gate. 7. In a game apparatus, a platform having a plurality of spaced holes at one end thereof, a registering member in association with 20 each of the holes, a trip member in association with each of the holes and operatively connected to the registering member of the respective hole for shifting said registering member into view when a ball enters the hole, 25 a gate member in association with all of the trip members for retaining the balls thereon and the respective registering member in view, said gate being shiftable for releasing all of the balls for permitting the trip members and registering members to assume their normal inoperative positions, a ball return 30 alley for receiving the balls when released by the gate, other gate means in association with the return alley adapted to close the 35 same when the balls are released by the first gate, means for opening and closing said gate, means connecting the gate to the gate means, and means for retarding the closing of the gate. 40 8. In a game apparatus, a platform having a plurality of spaced holes at one end thereof, a registering member in association with each of the holes, a trip member in association with each of the holes and operatively connected 45 to the registering member of the respective hole for shifting said registering member into view when a ball enters the hole, a gate member in association with all of the trip members for retaining the balls thereon and 50 the respective registering member in view, said gate being shiftable for releasing all of the balls for permitting the trip members and registering members to assume their normal inoperative positions, a return alley extending 55 from the space adjacent the gate to the starting end of the platform, the balls being adapted to be removed from the latter end of the alley, a second gate in association with the alley at the latter end thereof, and a third 60 gate in association with the alley intermediate the first and second gates, means for simultaneously actuating all of said gates, the first and second gates being opened and closed simultaneously, and the third gate being closed and opened alternately with re- 65

spect to the first and second gates, and means for retarding the closing of the first and second gates and the opening of the third gate.

In testimony whereof, I have hereunto set my hand at Los Angeles, California.

HARRY T. NAUMAN.
